F. O. LUDLOW

FIRE RESISTING STRUCTURE

Filed June 23, 1927

Patented Dec. 13, 1927.

1,652,314

UNITED STATES PATENT OFFICE.

FREDERICK O. LUDLOW, OF ST. JOSEPH, MICHIGAN, ASSIGNOR TO THE COMPOUND AND PYRONO DOOR CO., OF ST. JOSEPH, MICHIGAN, A CORPORATION OF MICHIGAN.

FIRE-RESISTING STRUCTURE.

Application filed June 23, 1927. Serial No. 201,011.

This invention relates to improved means for rendering wooden structures and particularly doors and their panels, wainscoting, ceilings and partitions of buildings fire resistant and temporarily fire proof.

The invention is especially applicable to doors and the like made with a thick core with surface veneer sheets secured to opposite sides thereof.

10 The object of the invention is to interpose between the core and each veneer surface sheet materials of such a kind and construction that a greater fire retardation and insulation is obtained than with the ordinary use 15 of asbestos, well known in the art.

The invention consists in devices attaining the foregoing and other objects, which can be easily and cheaply made, which are satisfactory in use and not liable to fail while 20 in use.

More particularly the invention consists in combining the strength, rigidity and density of a metal sheet with the insulating value of an asbestos sheet, this double protective layer or sheathing being interposed 25 between a thick combustible core and a thin combustible veneer.

The invention further consists in means for securing all the parts entering into the 30 door together and in numerous features and details of construction hereafter more fully set forth in the specification and claims.

Referring to the drawings in which like numerals represent the same parts throughout the several views:

Figure 1 is a perspective view and Figure 2 a sectional, detail view on the line 2-2 of Figure 1, illustrating the possible use of this 40 invention in which only metal sheets are used in combination with wood in producing the finished structure.

Figures 3 and 4 are corresponding views of the preferred construction of this invention in which sheets of metal and asbestos are 45 combined with wood in effecting the desired results of this invention.

In the structure of Figure 1, a thick wooden core 10 is provided, having two opposite exterior sheets of veneer 12 and 14, secured to opposite sides thereof. The fire-proofing result desired is attained by interposing between the core and each veneer surface the metallic sheets 16 provided with a multiplicity of generally conical indentations 18 driven into the adjacent surface of the core

10. The tops of the conical indentations 18 are, in the process of indenting, broken open, as shown, so as to leave ports or passageways 20 in the tops of the cones through which glue 22, interposed outside the metal sheet 16, may contact with and adhere to the wood of the core 10. This glue material 22 performs the additional function of securing the adjacent veneer sheet, as 12, in position, as clearly shown in the lefthand half of Figure 2.

In the preferred form of construction shown in Figures 3 and 4, a central core 24 and veneer sheets 28 and 28 are substituted for the wooden parts shown in Figure 1. A metal sheet 30 of the same general form is substituted for the metal sheet 16 of Figure 2. To the back or outside of each metal sheet 30 is secured by glue 32 an asbestos sheet 34 pressed into the conical indentations 36 of metal sheet 30 corresponding to the conical members 18 of Figure 2. Glue 38 is applied to the rear or outside surface of the asbestos sheet 34 for the purpose of securing the adjacent veneer sheet, as 28, in the lefthand side of Figure 4.

The indented members 18 and 36 have been referred to as conical. As shown in the drawings in which these indentations are in fact rectangular, there is no limitation in this phrase to any particular cross-sectional form as circular or rectangular.

The conical indentations 18 and 36, referred to, perform the valued function of affording resistance to the shearing strain in the glue joints between the various sheets of material. They also form a very important feature of providing in their broken, open tops means for the escape of gases set free from the body of the core 10 or 24, as the case may be, under fire conditions, it being well known that if no vent or escape is provided for a structure of this kind, the pressure of gases created in the core under heat against the door or the like using the construction of this invention tends to loosen or blow off the protective layer or sheath which is attached to the core. The indenting of the double protective sheathing of Figures 3 and 4 is further useful in obtaining the glue bond for the thin veneer laid over the structure so as to provide a finished surface for paint or stain. The strength of this glue bond is greatly enhanced by portions of the glue entering the indentations and adhering directly

to the core at frequent intervals as shown in the drawings.

Actual tests have demonstrated that the use of the metal sheets 16 and 34 greatly increases the fire resistance of structures of this kind as compared with prior structures in which only asbestos is used. Actual tests of structures of this kind under fire conditions have shown that the veneer sheet on the

10 fire side may be burned away and the core partially or completely charred and yet the door or other wall constructed in accordance with this invention stands as a barrier to the progress of fire because of the metal sheet adjacent to the fire having sufficient strength to stand up during the fire and retain its position glued to the charred core of the door or the like built in accordance with this invention.

20 Having thus described my invention, what I claim as new and desire to secure by Letters Patent is:

1. In a fire resisting structure, a combustible core, a metallic sheet adjacent to and indented into the core, the tops of the indents being perforated, adhesive material outside the metal sheet extending through the indents and a sheet of different mate-

rial secured in place by said adhesive material.

2. In a fire resisting structure, a combustible core, a metallic sheet adjacent to and indented into the core, the tops of the indents being perforated, adhesive material outside the metal sheet extending through the indents and a sheet of veneer secured in place by said adhesive material.

3. In a fire resisting structure, a combustible core, a metallic sheet adjacent to and indented into the core, the tops of the indents being perforated, adhesive material outside the metal sheet extending through the indents and a sheet of asbestos secured in place by said adhesive material.

4. In a fire resisting structure, a combustible core, a metallic sheet adjacent to and indented into the core, the tops of the indents being perforated, adhesive material outside the metal sheet extending through the indents, a sheet of asbestos secured in place by said adhesive material and a sheet of veneer secured to the outside of the asbestos.

In witness whereof, I have hereunto subscribed my name.

FREDERICK O. LUDLOW.
